UNITED STATES PATENT OFFICE

106,562

DESIGN FOR A BURIAL CASKET

Alfonzo C. Castillo, Albuquerque, N. Mex.

Application June 28, 1937, Serial No. 70,105

Term of patent 7 years

To all whom it may concern:

Be it known that I, Alfonzo C. Castillo, a citizen of the United States, residing at Albuquerque, county of Bernalillo, and State of New Mexico, have invented a new, original, and ornamental Design for a Burial Casket, of which the following is a specification, reference being had to the accompanying drawing, forming a part thereof.

I claim:

The ornamental design for a burial casket as shown.

ALFONZO C. CASTILLO.
